UNITED STATES PATENT OFFICE

106,995

DESIGN FOR A DESK LAMP OR SIMILAR ARTICLE

Lemuel L. Stewart, Chicago, Ill., assignor to The Adlake Company, a corporation of Illinois

Application May 10, 1937, Serial No. 69,263

Term of patent 14 years

To all whom it may concern:

Be it known that I, Lemuel L. Stewart, a citizen of the United States of America and a resident of Chicago, county of Cook, and State of Illinois, have invented a new, original, and ornamental Design for a Desk Lamp or Similar Article, of which the following is a specification, reference being had to the accompanying drawing, forming a part thereof, wherein

The figure is a perspective view of a desk lamp or similar article showing my new design.

The upright portion of the lamp is interiorly secured to the shade at substantially the center of the back of the shade. The standard and shade are substantially the same in shape and design on the reverse sides as they are on the sides which are visible.

What I claim is:—

The ornamental design for a desk lamp or similar article, substantially as shown, and described.

LEMUEL L. STEWART.
